UNITED STATES PATENT OFFICE.

WALTER STOFFEL, OF GREENLEAF, KANSAS.

WELL-DRILL COUPLING.

Application filed February 28, 1923. Serial No. 621,888.

To all whom it may concern:

Be it known that I, WALTER STOFFEL, a citizen of the United States, residing at Greenleaf, in the county of Washington and State of Kansas, have invented certain new and useful Improvements in a Well-Drill Coupling, of which the following is a specification.

The present invention relates generally to 10 couplings and more particularly to well drill couplings and has for its principal object to provide means whereby the drill bit may be attached to the drill stem by the usual threaded structure and prevented from 15 accidental rotation when once assembled.

Another important object of the invention is to generally improve upon couplings of this nature by providing a simple and efficient structure which is reliable, durable, 20 comparatively inexpensive to manufacture, and otherwise well adapted to the purpose for which it is designed.

A particular object of the invention is to provide a novel pawl and ratchet mechanism including means for holding the pawl in an inoperative position.

With the above and numerous other objects in view as will appear as the description progresses, the invention resides in certain 30 novel features of construction, and the combination and arrangement of parts as will be hereinafter more fully described and claimed.

For the purpose of illustrating my invention, I have shown in the accompanying drawing that form thereof which is at present preferred by me since the same will give in practice satisfactory and reliable results, although it is to be understood that 35 the various instrumentalities of which my invention consists can be variously arranged and organized and that my invention is not limited to the precise arrangement and organization of these instrumentalities as 40 herein shown and described.

In the drawing—

Figure 1 is a longitudinal sectional view of a drill stem connected to a drill bit both embodying my invention,

Figure 2 is a transverse section taken substantially on the line 2—2 of Figure 1,

Figure 3 is a similar view taken substantially on the line 3—3 of Figure 1, also showing the pawl releasing means associated therewith,

Figure 4 is a detail section taken substantially on the line 4—4 of Figure 3, and

Figure 5 is a detail perspective of one of the pawls used in conjunction with this invention.

Referring to the drawing in detail, it will be seen that the present embodiment of the invention includes a drill stem 1 and a drill bit 2 which may be of conventional construction except as hereinafter claimed. The drill stem is constructed with the threaded recess 3 extending longitudinally thereof and communicating with the internal ratchet arrangement 4 at the end of the drill stem. The drill bit 2 is provided with a threaded reduced extension 6 adapted to be received within the threaded recess 3. A plurality of pawls 7 are carried by the drill bit for engagement with the ratchet arrangement 4.

As is disclosed to advantage in Figure 5 each pawl 7 consists of a body 8, a stem 9 extending from one end of the body and a pintle 10 extending from the other end of the body and shorter in length than the stem 9.

In the present embodiment of the invention I use two pawls 7 and therefore provide the end of the drill bit adjacent the reduced threaded extension 6 with a pair of oppositely disposed deep recesses 12 and a pair of oppositely disposed shallow recesses 13. One recess 12 is situated adjacent one recess 13, the distance therebetween being the same as the distance between the stem 9 and pintle 10 of one of the pawls 7. A compressible coil spring 14 is disposed in each deep recess 12 as is also the stem 9 of the pawl 7 and the pintle 10 is situated in the shallow recess 13 adjacent thereto. This pawl is adapted to pivot on its pintle and to engage the ratchet arrangement 4, the spring 14 normally holding it in engagement therewith. As is illustrated to advantage in Figures 1 and 3 orifices 16 lead into the deep recesses 12 transversely of the drill bit and these orifices are threaded so that they may be closed by threaded plugs of any suitable construction which are not illustrated in the drawing. The purpose of such plugs is merely to prevent water and mud from entering the orifices and contacting with the working parts of the coupling when the same is in operation.

It will be readily understood that as the

invention has thus far been described the drill stem and drill bit may be readily assembled by screwing the threaded extension 6 into the threaded recess 3 and the pawl 5 and ratchet arrangement described will prevent the unscrewing thereof. When it is desired to disassemble the drill bit from the drill stem it is necessary to use a tool such as I have indicated generally at A. This tool A consists of an arcuate shaped body portion 20 one end of which terminates in an apertured lip 21 and the other end in a finger 22 which is aligned with the aperture of the lip 21. A threaded bore 23 is 15 mounted in the aperture of the lip 21 and is constructed with a finger 24 at its end adapted to align with the finger 22. These fingers 22 and 24 may be readily disposed in the orifices 16 thereby engaging the stem 20 20 and compressing the spring 14 so as to pivot the pawls upon their pintles 10 and disengage them from the ratchet arrangement 4. When the tool has thus been engaged with the pawls it is evident that the 25 drill stem and drill bit may be disassembled.

Having thus described my invention what I claim as new is:—

1. In combination, a pair of members associated in rotatable relation with each other, one of said members provided with a ratchet structure, a pawl associated with the other member for engagement with the ratchet structure, said latter mentioned member provided with a pair of recesses, 30 said pawl provided with a stem disposed in one recess and a pintle disposed in the other recess, a spring disposed in the recess containing the stem and normally urging the pawl in engagement with the ratchet structure, and means for engaging the stem for moving it and actuating the pawl from engagement with the ratchet structure so that the members may be rotated.

2. In combination, a pair of rotatably as-

sociated connectable members, a pawl and 45 ratchet mechanism associated with the members, one of said members containing the ratchet and the other containing the pawl, said pawl containing member constructed with a pair of recesses, said pawl provided with a pair of extensions disposed in said recesses so that one extension acts as a pintle 50 and the other as a stop limiting the movement of the pawl, a spring engaged with the stop extension for normally urging the 55 pawl in an operative position, said last mentioned member provided with an orifice leading into the recess containing the stop extension.

3. A pair of rotatably engageable members, a ratchet structure included in one of said members, a pawl structure included in the other member, said pawl including structure having means for pivotally mounting the pawl and a recess, said pawl provided with a stem extending in said recess, a spring in said recess engaging said stem and normally urging the pawl in engagement with the ratchet structure, said last mentioned member having an orifice leading 70 into its recess whereby a tool may be inserted therein for engagement with the stem and actuating the pawl from engagement with the ratchet structure.

4. A pawl releasing tool including an arcuate body terminating at one end in an apertured lip and at its other end in a finger disposed in alignment with the apertured lip, a threaded bar associated with the apertured lip and provided with a finger aligned 75 with the first mentioned finger.

In testimony whereof I affix my signature in presence of two witnesses.

WALTER STOFFEL.
